At this

UNITED STATES PATENT OFFICE.

REUBEN B. BENJAMIN, OF CHICAGO, ILLINOIS, ASSIGNOR TO THE BENJAMIN ELECTRIC MANUFACTURING COMPANY, OF CHICAGO, ILLINOIS, A CORPORATION OF ILLINOIS.

PLURAL-LAMP SOCKET.

SPECIFICATION forming part of Letters Patent No. 721,779, dated March 3, 1903.

Application filed July 18, 1902. Serial No. 116,083. (No model.)

To all whom it may concern:

Be it known that I, REUBEN B. BENJAMIN, a citizen of the United States, residing at Chicago, in the county of Cook and State of Illinois, have invented a certain new and useful Improvement in Plural-Lamp Sockets, of which the following is a full, clear, concise, and exact description, reference being had to the accompanying drawings, forming a part 10 of this specification.

My invention relates to improvements in plural-lamp sockets, my object being to provide a construction in which the lamp-holding devices and their associated contacts are 15 all carried upon the cover.

In the accompanying drawings, in which the same reference characters designate like parts throughout the several views, Figure 1 is a sectional view of one form of my invention. Fig. 2 is a detail view of the rings for attaching the inner ends of the inner and outer contact-plates together and looking upwardly in Fig. 2. Fig. 3 is a rear view of one of the lamp-holding devices. Fig. 4 is a sectional view of a slightly-different form. Fig. 25 5 is a front view of one of the lamp-holding devices. Fig. 6 is a rear view of the insulating-receiver. Fig. 7 is also a sectional view, but of different form. Fig. 8 is a face view 30 thereof with the central portion of the cover removed. Fig. 9 is a rear view of one of the lamp-holding devices, and Fig. 10 is a detail view of one of the outer contacts.

Referring to Fig. 1, a base 2, preferably of 35 metal, is provided with a central raised portion upon which the bolt or screw 3 is carried, a jam-nut 4 being employed to secure the same rigidly in place. The cover 5, also of metal, rests upon the edge of the base 2 and 40 supports the lamp-holding devices and the contacts therefor. These devices comprise the insulating-block 6, of the outline indicated in Fig. 3, secured to the cover by bolts 7 and having a rib 8 projecting through the 45 apertures in the cover. In the device shown at the left the metallic threaded shell 9 projects nearly through the block 6 and is soldered to the ring 10, carried upon and secured to the rear face of the block 6, which ring is 50 provided with an extension 11, to which the

segmental strip 12 is secured. The inner contact for the device comprises the spring-strip 13, secured at its outer end to the block 6 and passing diametrically across the aperture in the block, as shown in Fig. 3, its inner end 55 being secured to a similar segmental ring 14, as shown in Fig. 2. The intermediate portion of said strip forms the center spring-contact for the lamp. The right-hand socket is constructed similarly, except that the aperture 60 in the block 6 is itself threaded to receive the lamp-bases, and the outer contact is formed by the spring-strip 15, placed in a groove or depression in the edge of the threaded aperture, whereby it bears upon and makes contact with the lamp-shell when it is inserted 65 in the socket. This strip 15 is secured to the base, as by a screw placed at 16, while its opposite end is secured to the strip 12. The inner contact 13 of this device is secured to the strip 14, so that the inner contacts are electrically connected and the outer contacts are 70 electrically connected. Binding-screws 17 and 18 are carried by strips 12 and 14, respectively, to which the circuit-conductors 18^a and 19 are secured. The cover may be secured 75 at its edge to the base by screws or by soldering, in which latter case a removable cap 20, held in place by the bolt 3, serves to close the opening in the cover 5. In case the cover is 80 not secured to the base, the cover and cap are secured to the base by the screw 3. By removing the nut 20^a the cap and cover may be detached from the base. Suitable apertures 85 21 in the base permit the passage of the leading-in conductors.

In Fig. 4 the cover 22 is secured to the support by suitable screws 23, a piece of asbestos 24 or analogous material being placed across the opening of the cover. Insulating-blocks 25 of the form shown in Fig. 6 are secured upon the inside of the cover by suitable screws 26, while a projecting rib 27 extends through the cover. At the left-hand device a metallic threaded shell 28, provided 90 with an inwardly-turned flange 29 at its rear end, is carried in the aperture in the block and is secured in place against the back piece 30 of the insulating-block 25 by the segmental strip 31, having an extension 95 100

32 projecting to the rear through an aperture in the said block. A ring or half-ring 33 connects the inner ends of these pieces 32 and carries a binding-screw 34, to which one of the circuit-wires brought in through an aperture 35 in the support is secured. The inner contact is formed by the strip 36, extending back over the rear face of the back piece 30 of the block 25 and secured thereto by screws 37, which may be inserted through a suitable aperture 38 in the spring-contact end of the strip 36. The inner ends 39 of these strips are attached to the ring or part ring 40, having a binding-screw 41. In the right-hand device the block is itself threaded to receive the lamp-base, while the inner contact is formed by a strip secured by screw 43 and passing out through an opening in the block 25 and is secured to the ring 33. The outer contact is formed by strip 44, located in a slot at the edge of the aperture in the block 25 and is secured in place by screw 45. The end of this strip is then fastened to the ring 40. An aperture is provided in the end of the spring-contact 42 to permit placing screw 45 in position. The lamps are thus seen to be connected in parallel, although an outer and an inner contact of the two sockets are directly joined. A removable cap 46 may be readily taken off to get at the connections of the cluster.

In the remaining figures I show a cluster in which the binding-posts are carried upon an insulating-base and the lamp-holding devices and their contacts upon the cover. The individual devices are like the left-hand device of Fig. 4 and are shown in rear view in Fig. 9, the strip 31 being shown in detail in Fig. 10. The rings 33 and 40 are the same as in the previous figure and connect like contacts of each device. An insulating-base 47, however, is provided upon which the spring-strips 48 and 49 are secured by screws 50 and carry binding-posts 51. The outer ends of these strips are designed to engage the rings 33 and 40 when the cover is in place thereon, whereby it is only necessary to first secure and wire up the base when the cover, with the lamp devices, may be readily placed thereon, the bolt 52 serving to support the same. Suitable apertures are of course provided in the base for the passage of the circuit-conductors and base-securing screws.

In an application filed by me July 18, 1902, Serial No. 116,082, I have included generic claims covering the structure of this application, and this application is to be considered as subsidiary to said application above mentioned so far as the claims of said application are readable upon the structure of the present application.

Having described my invention, what I

claim as new, and desire to secure by Letters Patent, is—

1. In a plural-lamp socket, the combination with a metallic shell having a plurality of openings, of a plurality of insulating-blocks mounted upon said shell one opposite each of said openings, and a lamp-holding device and associated contacts mounted upon each of said insulating-blocks, substantially as described. 65

2. In a plural-lamp socket, the combination with a metallic shell having a plurality of openings, of a plurality of insulating-blocks one opposite each of said openings, each of said blocks having a threaded aperture for the reception of the lamp-base, a rib projecting through the opening in said shell and laterally-extending portions resting against the inner face of said shell and secured thereto, and a pair of contacts mounted upon said insulating-block, substantially as described. 75 80

3. In a plural-lamp socket, the combination with a metallic shell having a plurality of openings, of a plurality of insulating-blocks 85 mounted upon said shell, one opposite each of said openings, a lamp-holding device and associated contacts carried upon each of said blocks, and electrical conductors connecting said contacts in circuit relation also mounted 90 upon said shell, substantially as described.

4. In a plural-lamp socket, the combination with a metallic shell having a plurality of openings, of a plurality of insulating-blocks mounted upon said shell, one opposite each 95 of said openings, a lamp-holding device and associated contacts carried upon each of said blocks, and metallic strips connecting said contacts in circuit relation, substantially as described. 100

5. In a plural-lamp socket, the combination with a suitable base or support, of a metallic shell mounted thereon and provided with a plurality of openings, a plurality of insulating-blocks mounted upon said shell opposite 105 said respective openings, and a lamp-holding device and associated contacts carried upon each of said insulating-blocks, substantially as described. 115

6. In a plural-lamp socket, the combination with a metallic shell having a plurality of openings, of a plurality of insulating-blocks mounted upon the inner face of said shell one opposite each of said openings, and a lamp-holding device and associated contacts carried upon each of said insulating-blocks, substantially as described. 110

In witness whereof I have hereunto subscribed my name in the presence of two witnesses.
